CLAIM

The ornamental design for a microphone attachable to computer monitor, as shown and described.

DESCRIPTION

FIG. 1 is a front, top, and right side perspective view of the microphone attachable to computer monitor, the broken line showing of the monitor is for illustrative purposes only and forms no part of the claimed design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The wire is shown broken away on FIGS. 1-3 and 5-7 for ease of illustration.
